Beaverton, Oreg., a corporation of Oregon

Filed Feb. 27, 1967, Ser. No. 5,957

Term of patent 14 years

(Cl. D14—3)

FIG. 1

FIG. 1 is a perspective view of a cart for transporting a cathode ray oscilloscope, showing my new design;

FIG. 2 is a side elevation thereof;

FIG. 3 is a front elevation thereof; and

FIG. 4 is a rear elevation thereof.

The broken lines representing the oscilloscope in FIG. 1 are for illustrative purposes only.

I claim:

The ornamental design for a cart for transporting a cathode ray oscilloscope, as shown and described.
